UNITED STATES PATENT OFFICE

ROBERT R. MYERS, OF LAS VEGAS, NEVADA, ASSIGNOR TO CLEAN-BE-TWEEN TOOTH BRUSH COMPANY, OF ST. LOUIS, MISSOURI, A CORPORATION OF DELAWARE

TOOTHBRUSH

Application filed November 19, 1927, Serial No. 234,457, and in Germany November 22, 1926.

This invention relates to improvements in tooth brushes, and especially to a separable handle or holder for tooth brushes having adjustable and replaceable brush heads.

5 The subject matter of the present application constitutes a continuation in part of that originally included in my copending application, Serial No. 49,762, filed August 12, 1925.

An object of this invention is to provide 10 a clamping device for the adjustable retention of a brush head, and which will permit the brush head to be readily moved to any desired angle with the longitudinal axis of the handle, and frictionally retained in the 15 adjusted position.

A further object is to provide a brush holder which will permit of the easy attachment or removal of a separate brush head, so that the latter may be easily renewed.

20 A further object is to provide a handle, for the described purpose, with an enshrouded clamping device for a brush head, so that the exterior surface of the assembly will be smooth, free from projections, and avoid injury to the oral cavity and gums, when employed with a tooth brush.

Further objects and advantages of the invention will appear from the drawing and the following detailed description.

30 It will be understood that the described clamping device and handle, may be varied substantially as to the proportion and disposition of their various parts; that the clamping device may be slightly modified in 35 form and thereby adapted for use with a brush head of a modified form; that if preferred the handle proper and portions of the clamping device may be integrally formed, instead of being constructed of different 40 parts; that the foregoing and other changes may be made in the described example, the same being merely a single executional embodiment of my invention which is submitted in compliance with the statutory requirements relating to applications for Letters 45 Patent.

Referring to the drawings, Fig. 1 is a side elevation of a complete brush, the handle and clamping device of which is constructed 50 in accordance with the present invention;

Fig. 2 is a plan view of the handle; and Figs. 3 and 4 are enlarged fragmentary views of the brush end of the handle, certain parts being shown in section.

With particular reference to the drawings, 55 5 indicates the brush handle, proper, which is substantially flat and curved at its outer end to conform to the hand of the user. The handle may be constructed of any desired material having the requisite strength. Secured to the outer end of the handle, in a suitable manner, is a metal member 6, provided just beyond its point of attachment to the handle 5 with an elongated opening 7. From this point the metal member 6 is extended to form an outer end 8, which is preferably of tubular form and elliptical in cross section. The metal member 6 terminates in a flared portion 9, at the extreme outer end of the member 6, and of the brush handle. 70

Mounted partially within the tubular portion 8 is a clamping device 10, which preferably consists of a flat metal member provided with a circular head 11, having a circular opening 12, and a slot 13, formed therein. 75 The opening 12 is adapted to receive the brush head in a manner which will be hereinafter more fully described. By reason of the slot the clamping device has a pair of oppositely disposed members 14 and 15 which taper inwardly from the outer end portion to the rear portion of the member 8, into a pair of spring clamping arms 16 and 17. By preference, the clamping device terminates at its inner end in a threaded stud 18 on which may be threaded an adjusting nut 19. A portion of the outside surface of the adjusting nut is preferably exposed at the top and bottom of the handle as shown, in order to provide for easy access to the nut 19 when securing the 80 handle and a brush head together.

The advantages and manner of use of the described brush handle and clamping device, are thought to be apparent from the above detailed description of parts. It will be seen 95 that the adjusting nut 19 is located with respect to the handle so as to be readily accessible for rotation by the thumb and first finger of the user. By rotating the adjusting nut 19, the clamping device 10 will be drawn 100

rearwardly. It will be seen that the inner surface of the portions 8 and 9, will constitute a slidable bearing surface for either forward or rearward movement of the element 10. The flared outer end 9 of member 6 serves to govern the clamping action of the spring arms 16 and 17. The inherent resiliency of these members serves to release them from about the brush head as soon as clamping device 10 is moved forward a sufficient distance. The adjusting nut 19 is positioned longitudinally by contact of the ends thereof with the ends of the elongated opening 7, as will be obvious from the drawing.

15 As the brush is secured to the handle solely by frictional engagement with the handle clamping member, it will be noted that the described construction of the handle and the clamp permits the brush to be readily turned and adjusted to various positions without operating the adjusting nut.

The brush handle and clamp may be formed entirely of such metal as German silver or monel metal, so that the entire brush 25 may be sterilized by boiling without damage, corrosion or discoloration.

It appears to be accepted by the dental profession that the teeth should be cleansed in a vertical direction toward and away from the 30 gums, and by providing a handle which permits the use of a comparatively small, angularly adjustable, brush that may be instantly adjusted at various angles with the handle, a brush assembly is provided which will facilitate brushing the teeth in the described manner.

I claim as my invention:

In a holding device, adapted for use with a toothbrush having a stud for detachable engagement by said device, a tubular outer end portion, the inner end of the tubular portion opening into a nut-receiving aperture, a handle, a sleeve formed by said tubular portion and extending beyond said aperture, said 45 sleeve being crimped about a portion of the handle for securing of the handle to said tubular portion, a stud clamping member having a stud-receiving opening in its outer end, and a rearwardly extending slot leading 50 from said opening and adapted to engage in said tubular outer portion, whereby the size of the stud opening may be decreased in diameter, a threaded stud formed on the inner end of said clamping member, and a nut disposed 55 in the aperture of the tubular portion and engaging said threaded stud.

ROBERT R. MYERS.
